UNITED STATES PATENT OFFICE

2,455,518

INSOLE RIB CEMENTER

Hans C. Paulsen, Medford, Mass., assignor to
United Shoe Machinery Corporation, Flemington, N. J., a corporation of New Jersey

Application August 30, 1946, Serial No. 693,854

8 Claims. (Cl. 12—80)

1

This invention relates to insole rib cementers and is designed particularly to apply cement to the inner surface of the insole rib and to the adjacent channel in preparation for the application thereto of a strip of reinforcing canvas.

For many years, leather insoles having integral ribs formed by channeling and erected from the body of the insole have been reinforced by the application of a layer of canvas extending against the inner face of the rib. More recently, it has been found desirable to substitute strips of canvas for the over-all reinforcing and, in preparation for the attachment of such strips, it is customary to apply an adhesive, hereinafter called "cement," to the inner face of the rib, the adjacent channel and a small portion of the mid-surface of the insole. One highly satisfactory machine for that purpose is described in Letters Patent of the United States No. 2,400,163, granted May 14, 1946, upon the application of Hans C. Paulsen. In that machine, the application of cement is effected by means of a roll mounted on a horizontal axis with its end engaging the face of the rib. In order for this machine to deal with the rather sharp curvature at the toe of the insole, it is necessary to use an applying roll of small dimensions and, while the machine operates satisfactorily with a small roll, it increases the cost of manufacture and the possibility of breakage.

Accordingly, an object of the present invention is to devise a less expensive and more rugged machine of this type.

In accordance with a feature of the invention, the feeding of insoles having pointed toes is facilitated by applying the coating by means of a roll rotating about a vertical axis. This roll is arranged to grip the rib against the end face of an opposed feed roll and can easily handle ribs having a sharp curvature.

In the illustrated machine and in accordance with other features of the invention, cement is supplied to the periphery of the coating roll by means of a nozzle and the spreading of the cement in the channel is aided by a non-rotatable member positioned inside the applying roll and at its lower end. This spreader and the roll itself are individually yieldable heightwise to care for variations in thickness of the work and to enable a sure contact therewith throughout the cycle of the machine.

These and other features of the invention will best be understood from consideration of the following specification taken in connection with the accompanying drawing, in which

2

Fig. 1 is a side elevation of the head of the machine with the cover removed therefrom;

Fig. 2 is a similar view, but on a larger scale, of the work-engaging parts in their operating position;

Fig. 3 is an angular view, looking at the end portion of the parts shown in Fig. 2;

Fig. 4 is a detail horizontal section through the lower end of the applying roll on the line 10 IV—IV of Fig. 2 but enlarged and looking down upon a portion of a piece of work;

Fig. 5 is an angular view of the applying roll, the nozzle and other associated parts;

Fig. 6 is an end elevation of these parts;

Fig. 7 is a vertical section on a still larger scale through the coating roll and its supplying nozzle;

Fig. 8 is a section through the nozzle on the line VIII—VIII of Fig. 7; and

Fig. 9 is a greatly enlarged view of the bottom end of the applying roll, in inverted position, with the parts associated therewith.

As will be seen from Figs. 2 and 3, the machine is arranged to apply a coating of cement to the inner surface 10 of a rib 12 formed by channeling an insole 14 and sticking the erected channel flaps together. It is also arranged to apply cement to the bottom of the inner channel 16 and to an adjacent margin 18 of the surface of the mid-portion 20 of the insole. When the work is 25 in position in the machine, the feather 22 of the insole is gripped between a feed roll 24 mounted at the outer end of a horizontal shaft 26 and the periphery of a supporting roll 28 carried on a shaft 30 in a tiltable arm 32. The rib 12 is 30 gripped between the periphery of a coating roll 34 rotatable about a vertical axis and the end surface of the feed roll 24, and means are provided for spreading the cement deposited by the roll 34, as will be later described. This coaction 35 of the rolls 24 and 34 is particularly valuable where sharp-toed insoles are to be treated, especially if the ribs have been slashed at the toe. In that case, the vertical roll 34 grips the successive slashed portions against the end of the roll 24 and feeds the insole without difficulty.

The shaft 26 of the feed roll 24 is journaled in a web 36 extending outwardly from the side of a hollow frame 38 (Fig. 1) and, within this frame, there is an arm 40 in which there is journaled a drive shaft 42 connected to the roll shaft 26 by means of gears 44 and 46. The arm 32 in which the supporting roll shaft 30 is journaled is tiltably mounted between pivot screws 48 extending inwardly from ears 50 formed on the inner side of 50 the frame. Rolls 24 and 28 are connected to turn 55

oppositely at equal speeds by a gear connection 52 between the roll shafts. The rotation of the coating roll 34 to coact with the other two feed rolls is effected by a gear connection 54 between the shaft 26 and a shaft 56 rotatable in the web 36 and connected, in a manner to be later described, with the coating roll. This roll 34 is journaled in a block 60 slidably mounted on pins 62 and 64 which are secured to and extend outwardly from the web 36.

When the operator presents a piece of work to the machine, he depresses a treadle connected to a treadle rod 66, thereby tilting a lever 68 which has an upwardly extending arm 70 and is also connected to a rod 72 yieldably engaging an extension 74 of the tilting arm 32. The movements of this extension 74 are limited by suitable stop screws 76 and 78. These stop screws are carried in a plate 80 secured to the inwardly extending arm 40. The tilting movement of the arm 32 lifts the supporting roll 28 into engagement with the lower face of the insole 14, raising the feather 22 thereof into engagement with the feed roll 24. At the same time, the block 60, carrying the coating roll 34 is drawn inwardly by reason of the action of the upper end 82 of the arm 70 in drawing inwardly a rod 84 having a hooked end 86 engaging a stud 88 (Figs. 1, 3 and 6) upon the block 60. Details of the construction of this rod 84 will be found in the earlier Paulsen patent mentioned above. To assist the operator in positioning the work and in guiding it, the machine is provided with an edge guide 90 (Figs. 1, 2 and 3) against which the periphery of the insole is rested as it is introduced into the machine. Further, there is a rib guide 92 having an inturned rounded end for engagement with the outer face of the rib of the insole to keep the rib from being overridden by the feed roll 24 in the case of limp or imperfect ribs.

The edge guide 90 is adjustably secured by a screw and slot arrangement 94 (Fig. 2) to a plate 96 (Fig. 3) attached to the arm 32 and, on this plate, there is also mounted a table 98 over which the bottom surface of the inverted insole rides as it moves in to the supporting roll 28. A resilient supporting member 100 attached to the plate 96 and positioned at the left of the supporting roll 28 (Fig. 1) helps to offset the tendency of the insole to tilt downwardly, especially if it is of light material. A scraper 102 (Fig. 3) engages the downgoing side of the supporting roll 28 to remove bits of cement accidentally deposited thereon. This scraper is carried by an arm 104 secured to a rod 106 which is journaled in a boss 108 depending from the plate 96. The rod 106 is provided with a torsion spring 110 holding the scraper 102 in firm engagement with the downgoing side of the periphery of the supporting roll 28. The rib guide 92 is adjustably positioned upon the lower portion of the web 36 by retaining screws 112.

It will be seen from Fig. 7 that the coating roll 34 is annular and is provided with an upwardly extending sleeve 120 which is journaled in the block 60 and receives power to rotate the roll 34 by means of a spiral gear 122 connected thereto by a key 124. This gear 122 engages a spiral gear 126 keyed to a short shaft 128 which is itself journaled in the block 60 and which is provided with an outwardly extending tongue 130 (Figs. 1 and 5) adapted to be received in and to slide lengthwise of a slot at the end of the shaft 56. Accordingly, the movements of the block 60 upon the rods 62 and 64 do not interfere with the continuous drive of the applying roll 34.

This roll itself is received in an enlarged recess 132 (Fig. 7) in the block 60 in which there is positioned a coil spring 134 surrounding the sleeve 120 and urging the roll downwardly. This downward movement is limited, however, by a collar 136 held at the upper end of the sleeve 120 by a setscrew 138. Provision is thus made for a limited upward yielding movement of the coating roll such as may be required by thicker work. Within 10 the sleeve 120 there is a vertical rod 140 the lower end of which has an enlarged portion constituting a fixed spreader 142 to aid in coating the channel. This spreader has its bottom end surface provided with grooves 144 (Figs. 4 and 9) which overlie the margin 18 of the mid-portion 20 of the insole and assist in spreading the coating of cement deposited thereon by reason of gravity flow down grooves 146 in the periphery of the applying roll. Half of the latter grooves are extended as at 148 (Fig. 9) to an annular recess 150 at the lower end of the applying roll adjacent to the fixed spreader 142 and facing the channel 16. Formed upon and extending at a different level slightly below that of the major part of the bottom end of the spreader 142 is a ribbed portion 152 which projects into the channel 16 and serves to make sure that the cement is spread over the whole surface of that channel. A small lip 154 on this spreader extends out nearly to the periphery of the applying roll and is intended to extend almost to the inner face 16 of the rib 12 of the work.

In order that this spreader shall be vertically yieldable to accommodate various thicknesses of work, the upper end of the rod 140 is provided with a cylindrical block 156 which is held in adjusted position on the rod 140 by a setscrew 158. A groove is provided at the upper end of this cylindrical block to receive the horizontal portion of an arm 160 (Figs. 1 and 5) which has a depending portion received in a groove in the side of the block 60 and is attached thereto by screws 162 (Fig. 5). Between the arm 160 and a recess 164 in this cylindrical block 156 is a coil spring 166 surrounding the rod 140. To facilitate the assembly of the machine, a collar 168 is secured to the upper end of the rod 140. The limit of upward movement of the rod 140 is determined by the engagement of the cylindrical block 156 with the arm 160, and a limit for the upward movement of the coating roll 34 is provided by a sleeve 168 having depending legs 170 (Fig. 6) which rest upon the upper surface of the collar 136. The sleeve 168 is notched at 172 to receive the arm 160 and acts by engagement with this arm to limit the upward movement of the collar 136.

Coating material such as latex is supplied under moderate pressure to the applying roll 34 by means of a nozzle 174 curved to partly surround the lower end of the applying roll as best shown in Fig. 5, and provided with dual passages 176 (Fig. 8) terminating in outlet openings 177 (Figs. 4 and 8) in the curved surface of the end of the nozzle at a point well up on the side of the applying roll. These passages are tapered and the flow through them is controlled by needle valves 178 mounted at the lower end of a stem 180 which passes through a packing gland 182 formed in a body member 184, the latter having a depending neck 185 to which the nozzle 174 is attached. At the upper end of the stem 180 is a pivot pin 186 surrounded by a spring 188 the compression of which may be adjusted by turning a knurled cap 190 threaded in the upper end of the body member 184. A bell crank lever 192 (Fig. 8) pivoted on

a screw 194 which is attached to the body member 184 is forked at its lower end 196 and underlies an enlarged portion 198 of the stem 180 in a recessed portion of the body member. On the upper arm of this bell crank 192 is a flanged stud 200 which is positioned for engagement in the forked end 202 of a rod 204 (Fig. 1) which is slidably mounted in the side of the frame 38 of the machine and is normally pressed outwardly therefrom by a spring 206. A collar 208 limits the extent of outward movement. The arrangement is such, therefore, that, when the block 60 on which this nozzle is mounted, as will be later described, is drawn inwardly by the hooked end 86 of the treadle controlled rod 84, then the bell crank is tilted by the resistance of the rod 204 and the needle valve is lifted.

Coating material such as latex is supplied to a passage 210 (Fig. 8) leading to the nozzle 174 through a flexible tube 212 (Fig. 1) which is clamped to a supply pipe 214 having at its lower end a sleeve 216 surrounding a hollow stud 218 which communicates with the passage 210. The mid-portion of this stud is reduced, and two passageways 220 at right angles to each other connect the reduced portion of the outside of the stud to the central passage therein. This arrangement permits free swinging movement of the supply pipe and the tube as the block 60 is moved in and out and does not interfere with the positioning of the nozzle with respect to the applying roll. Adjustment of this position is effected by loosening a clamp screw 222 (Fig. 7) threaded in the nozzle body 184 and passing through the slotted end of a mount 224 the face of which is grooved to coat with a rib on the body portion 184. In this mount is a stud 226 held in position by a setscrew and the stud passes through an outwardly extending portion of a support 228 (Fig. 6) adapted for heightwise adjustment upon the block 60 with the aid of a rib 230 after which the support may be secured in adjusted position by means of a clamp screw 232 passing through an elongated slot in this support. The tilted position of the nozzle upon the support 228 to bring the outlets 177 close to the roll 34 is maintained by a drawbolt 234 in the support engaging the side of the stud 226.

As will be plain from Figs. 1 and 2, the nozzle 174 is mounted on the near side of the applying roll toward which the ingoing work moves as it is fed forward, and it will be noted from Fig. 2 that an extension lip 236 is provided on the lower end of the nozzle which rests in the channel 16 of the insole and helps to hold the latter against the supporting roll 28 so that, if the insole happens to be made of poor material, there will be less opportunity for the feed wheel 24 and the applying roll 34 to ride accidentally over the rib. It frequently becomes necessary to supply the latex in such quantities that the applying roll is flooded and, then, in order to prevent the latex from working up between the side of the applying roll and the recess 132 (Fig. 7) in which it rotates, the periphery of the roll is provided with a helical groove 238 tending always to push the latex downwardly out of this joint.

As a further aid in spreading the cement which has been applied to the insole, there has been provided a tiltable drag 240 surrounding the far side of the applying roll and hence its leaving side, considered with respect to the direction of movement of the work as indicated by the arrows in Figs. 4 and 9. This drag 240 tapers downwardly toward the leaving side of the roll and terminates in a depending lip 242 (Figs. 6 and 7)

which rides in the channel 16 for the reason that the drag is tiltably mounted upon a screw 244 and is urged downwardly by a spring 246 to bring the lip portion 242 against the work. The lip 242 is not quite as wide as the channel to avoid binding on the work at the toe end thereof. In order to provide for adjustments in setting up the parts of the machine which are associated with the applying roll 34, the pivot screw 244, passing through a sleeve 248 (Fig. 2) which is integral with the drag 240, is threaded in the lower end of a hanger 250 (Fig. 3) adjustably attached to the side of the block 60 by a screw-and-slot connection 252. The upper end of this hanger 250 is received in a recess 254 in the block 60. It will also be seen from an inspection of Figs. 2 and 3 that the drag 240 has an integral flat plate 256 on the upper portion of which there is adjustably attached by screws a strip 257 (Fig. 20) having an outwardly extending ear 258 to which one end of the spring 246 is attached. The other end of the spring is looped about a pin 260 in the block 60.

In the operation of the machine, an insole 25 turned with its heel end away from the operator is moved laterally until its periphery contacts the edge gage 90. If, however, we are dealing with a so-called "cookie insole," then, the screw 94 will be loosened and this edge gage moved 30 out of the way to prevent interference with the extension in the shank of that kind of insole. At the same time, the outside of the rib 12 is pressed against the guide 92 and the treadle depressed which will raise the supporting roll 28 to lift the feather of the insole into contact with the under side of the feed roll 24 and the channel of the insole into contact with the tip 236 on the nozzle and with the bottom end of the applying roll. This action will also be accompanied by a 40 movement, to the right, of the rod 84 which will slide the block 60 and draw the applying roll 34 against the inner face 10 of the rib where it will be rotated in such a direction that its periphery moves with the rib of the insole as the latter is carried away from the observer in Fig. 1.

Since the inward movement of the block 60 will also be accompanied by an opening of the valve 178 in the nozzle, the coating material will 50 flow through the outlet openings 177 into contact with the side face of the applying roll 34, entering the grooves 146 to flow down against the insole and through the passages 148 (Fig. 9) into the annular portion 150 at the base of the applying roll. The cement will then be spread upon the mid-portion 20 of the insole to form the marginal band 18 with the assistance of the grooves 144 in the lower end of the spreader 142 and will be 55 spread out in the channel 16 by the ribs 152 and the extension 154 also at the lower end of this spreader.

Variations in thickness will be accommodated by the upward yielding of the spreader 142 against the resistance of the spring 164 (Fig. 7) and the roll 34 itself may yield upwardly against the resistance of the spring 134. A further spreading action is accomplished by the depending drag lip 242 which is held in yieldable engagement with the work by the spring 246.

Having thus described my invention what I claim as new and desire to secure by Letters Patent of the United States is:

1. In a machine for coating soles having an upstanding rib and an adjacent channel, an upright driven roll for coating one face of said

rib and an adjacent channel, means for supporting a sole with its rib in contact with the periphery of the roll and with said channel facing the end of the roll, said roll having grooves extending axially of the periphery thereof and an annular groove in its end face, said roll also having passages from said annular groove to some of the grooves on the periphery of the roll to permit coating material on the periphery to flow into the annular groove, and means for supplying coating material to said periphery above the lower end thereof.

2. In a machine for coating soles having an upstanding rib and an adjacent channel, an upright driven annular member having its periphery arranged for engagement with the rib, means for supplying coating material to the periphery of said annular member, a vertically yieldable member within and cooperating with said annular member having its lower end arranged for engagement with the channel to spread coating material which has run off the annular member, and means for presenting successive portions of a sole to said members.

3. In a machine for coating soles having an upstanding rib, a driven upright roll the periphery of which is arranged to coat the inside of the rib of a sole, means for supporting said roll to yield vertically, means to supply coating material to said roll, means for driving said roll, means to present a sole to the roll, and a spreading member supported at the lower end of the roll to yield vertically and held against rotation.

4. In a machine for coating soles having an upstanding rib and an adjacent channel, an upright driven annular coating roll mounted to yield vertically and rotatable about an upright axis to coat the rib, means to supply coating material thereto, a member which aids the coating of said channel positioned within said annular roll, and means to present successive portions of the margin of a sole thereto, the work-contacting surface of said channel coating member having grooves extending in the direction of presenting movement.

5. In a machine for coating soles having an upstanding rib and an adjacent channel, an upright roll for coating the inside of the rib, means for supporting a sole, means for feeding the sole to present successive portions of its rib to said roll, a fixed member at the bottom of said roll, the lower end of which is disposed at two different

levels thereby to contact with the bottom of the channel and with the adjacent surface of the insole, and means for supplying coating material to said roll.

6. In a machine for coating soles having an upstanding rib and an adjacent channel, means for supporting the sole, means for feeding the sole, an upright roll for coating the inside of the rib having a fixed central portion, the lower end of which is arranged to contact with the bottom of the channel, and a source of supply comprising a nozzle positioned ahead of the roll for supplying coating material to the peripheral surface thereof, the lower end of said nozzle having a depending portion for engagement in the channel of the insole.

7. In a machine for coating soles having an upstanding rib, a vertical roll the periphery of which is provided with upright grooves, means for presenting successive portions of a sole to said roll, a source of supply of coating material comprising a nozzle for delivering coating material to the front side of the roll toward which the sole is moved, and a drag surrounding a portion of the periphery of the roll, said drag having a lower edge which tapers downwardly toward the leaving side of the roll to spread coating material which has run off the lower end of the roll.

8. In a machine for coating soles having an upstanding rib, a vertical roll the periphery of which is provided with upright grooves, means for presenting successive portions of a sole to said roll, a source of supply of coating material comprising a nozzle for delivering coating material to the front side of the roll toward which the sole is moved, and a drag surrounding a portion of the periphery of the roll, said drag having a lower edge which tapers downwardly toward the rear of the roll, said drag being tiltably supported and spring-held with its lower end in engagement with the sole.

HANS C. PAULSEN.
